GAME DEVICE

Nelson Littell, New Canaan, Conn., and William Wenecek, New York, N. Y.; said Wenecek as signor to said Littell

Application January 11, 1934, Serial No. 706,184

16 Claims. (Cl. 273—29)

This invention relates to a new and useful improvement in a game of skill or amusement device for the solo playing of ping-pong, tennis and the like games requiring a ball to be bounced on a suitable table or court before being returned by the player.

One of the principal objects of the invention is to provide a game of skill consisting of a suitable ball projecting apparatus mounted with respect to a playing court such as a table or other playing surface to serve a succession of balls in sufficiently rapid order and at such different positions in the playing court that a player, by himself, can obtain the experience and thrill of playing the game as though opposite a skilled player.

Another object of the invention is to provide a game of skill for amusement parks or for the home which includes a ball projecting device having a hopper for a plurality of balls which will project them at variable rates of speed and at variable positions onto a court or table, from which they will bounce to the player who in returning them to the return court may determine his score or relative skill by suitable scoring mechanism of a type to give the score according to the form of scoring of the particular game.

An incidental object of the invention is to arrange the courts and scoring device so that when the projected ball is returned in a proper manner equivalent to a score, it may be replaced in the ball projecting device hopper for replay, whereas a ball which has not been properly returned will be temporarily out of the playing circuit.

Another object of the invention is to provide a novel ball projecting device operable on light weight balls such as table tennis or tennis balls, which will receive the balls, one at a time from a suitable hopper, and will discharge the balls, the rate of delivery and the speed of delivery and the point of delivery being irregularly variable so that it will be difficult to exactly determine the delivery point of the next ball.

Prior games and amusement devices of this general nature have been known in which baseballs are mechanically projected toward a batsman in the cage with the expectation that the batsman will strike the ball while it is in the air in much the manner in which the ball is struck in a baseball game. These prior baseball batting devices are not satisfactory for the large part of the public as women and children cannot successfully use the bat for the return of a ball projected in this manner and the danger

of being struck by one of these swiftly projected (solid) balls flying through the air is very substantial, especially for a timid person in the batsman's cage. These devices are also entirely unsatisfactory for other games requiring a delivery to variable locations or using a light ball such as ping-pong or tennis ball etc., and have never proven popular.

Our invention is to be distinguished from these prior baseball practice devices in that according to this invention the ball which is projected from the projecting machine first strikes upon the court or upon a table or target and is returned by the player on its bound or bounce. Although the player will use a racquet, or other striking medium or even his hand, the ball is of light weight and of the bouncing type and as it is always bounced prior to being struck the speed of the ball is retarded and the game is made safer and of a more universal appeal to men, women and children, who are accustomed to playing table tennis, tennis, badminton and similar games.

It will be understood that the invention may take various forms but in general it is the object of the invention to provide a game or amusement device in which a bouncing ball is projected so as to bounce in front of the player and is then returned by the player into a given field of play at the opposite side of the court or table which may or may not have an intervening net. If the ball is properly returned, it may be reconveyed to the projecting device for subsequent projection toward the player again or it may operate a scoring device which may take various forms and if it is not properly returned, it is "lost" for that particular period of play.

The projection device is preferably provided with a magazine of balls so that the player will not have to await the return of any particular ball, but once the game is started, he will be continuously supplied with balls served to different points in front of him until the period of play is ended or the original supply of balls has been exhausted through "loss" of the balls due to poor returns. Although the game may be played without reference to a charge and the apparatus as to delivery is the same whether controlled by a coin or operator, it is to be understood that the game apparatus is adapted for installation in amusement parks and to be so controlled that the player will pay a nominal fee for his period of use.

To more realistically approach playing conditions the serve is preferably by a variable speed

device and the speed of delivery as well as the angle of delivery may thus be controlled for the conditions of play. The device is thus adaptable to desired playing conditions making it possible to vary the speed for women as well as men to play.

Other objects and advantages of the invention will appear from the following description of preferred forms of embodiment thereof taken in connection with the accompanying drawings, in which:

Figure 1 is a side elevation of a tennis court with the projecting machine in position, the return channel with parts in section, being shown also.

Figure 2 is a plan view of a tennis court type of arrangement of our amusement device with one form of ball projection device in place,

Figure 3 is a reduced scale vertical section taken substantially on the line 3—3 of Figure 2 showing the channels for gravity return of the balls to the projection device,

Figure 4 is a larger scale side elevation with parts broken away of the projection device and mounting shown in Figures 1 and 2,

Figure 5 is a larger scale vertical section through the top only of one embodiment of projection device and taken along the line 5—5 of Figure 4, looking toward the rear,

Figure 6 is a substantially central, vertical section through the projecting mechanism of Figures 4 and 5,

Figures 7 and 8 are respectively top plan and side elevation detail views of the star wheel clutch mechanism in the projecting device of Figure 4,

Figures 9 and 10 are respectively end elevation and side elevations of the spring arm retarder in the projecting device of Figure 4,

Figures 11 and 12 are side elevation and plan views of a further embodiment of the invention in which the ball is bounced onto a table and is returned to the return court having a form of counting platform which automatically computes the score,

Figure 13 is an end elevation with parts in section of the projecting device and one type of score board which may be used in the embodiment of the invention shown in Figures 11 and 12,

Figure 14 is an enlarged perspective view, partly in section of the counting platform shown in Figure 12,

Figure 15 is a vertical section and Figure 16 is a vertical section taken substantially at right angles thereto on the line 16—16 of Figure 15, showing the counting members and actuating mechanism,

Figure 17 is a plan view of a modified court and table for playing table tennis or similar games illustrating the use of a different type of scoring mechanism,

Figures 18 and 19 are vertical sections and front elevational views of the pocket type of scoring mechanism,

Figure 20 is a diagrammatic view of a relay for the counting mechanism shown in Figure 18,

Figure 21 is a vertical section through a modified form of projecting device and elevator mechanism and,

Figure 22 is a top plan view, partly broken away, taken substantially on the line 22—22 of Figure 21.

While the game or amusement device of our invention may be embodied in various forms it consists generally of a court, table or playing surface indicated at 10 which may be marked out in suitable boundary lines 12 to resemble a tennis

court for example, a projecting device or gun 14 adapted to project balls into the playing court as desired, and a scoring or return area 16 which may be behind a net or dividing element 18 which divides the players zone 11 from the return zone 16.

The court 10 is also preferably provided with a slope to return the balls to a collection point and may be provided with channels 10a as shown in Figure 3, so that the balls 8 will roll by gravity 10 to a sump or receptacle 10b from which they may be automatically returned by the elevator 15 to the feed hopper 14a of the projecting device.

The projecting device 14 which will be hereinafter described is adapted to discharge balls 8, 15 such as table tennis or tennis balls at a suitable angle downward as represented by the dotted line 17 to the player's zone 11 from which it will bounce to the player holding a racquet or return device 19 who will return the ball to the scoring zone 16. By suitable means as hereinafter described, the score of the shot and the accuracy of the player may be registered. The balls may be discharged at any desired rate, preferably as rapidly as the skill of the average player will permit him to handle the same, and may be discharged with regulated speed to deliver a fast or slow ball as desired. The game may also be kept up as long as the operator desires, although a limited number of balls may be placed in the hopper for use 30 in amusement parks, etc., the supply being replenished on payment of the desired fee. Automatic means may serve to return the balls to a suitable overhead hopper from which a group of say twenty-five or fifty balls may be released into 35 the machine hopper by a coin control mechanism on payment of the established fee.

One form of gun or projecting device 14 is illustrated in Figures 4 to 10 inclusive, although it will be understood that other forms may be used. Such a device includes a hopper 14a which preferably opens into a reduced neck portion 14b which is of the size of a single ball 8 so that the balls will pass into the machine one at a time. Within the machine is a discharging arm of 45 catapult, centrifugal or compressed air type and in the particular type shown, consisting of a cup or ball receiving pocket 20 carried on the end of an arm 21 which moves about a central shaft 22, the control spring 23 also being wound on a 50 housing 23a mounted on the shaft 22. Preferably the ball discharging arm 21 is a continuation of the spring 23, the other end of the spring being secured in the adjustable member 24 as shown in Figure 6, whereby the device may be adjusted to 55 deliver a slow or fast ball.

The shaft 22 is driven through suitable gearing 26 from a continuously rotating motor 27 and keyed to the shaft is the discharge arm tensioning member 28 including the collar 28a and the star 60 wheel 30. The construction of this head is more particularly shown in Figure 7, and consists of a multi-toothed member centrally pivoted at 31 to the member 28 through the flange 32. The arm tensioning member 28 also carries a spring pressed 65 detent 33 adapted in normal condition to extend upward through an opening 34 in the star wheel 30 to hold the wheel in non-rotatable position. The detent 33 is provided with a releasing pin 36 whereby the detent when withdrawn will release 70 the star wheel 30 which in turn will release the discharge arm 21 to project a ball.

The arm engaging teeth 37 of the wheel 30 are within the path of the discharge arm 21 and during the rotation of the gearing by the opera- 75

tion of the motor 27, the arm engaging head rotates contacting with the discharge arm 21 to carry the catapult cup 20 into its rearward position as shown in dotted lines of position "A" in 5 Figure 6.

During this travel, however, the releasing pin 36 comes into contact with a releasing cam 38 fixedly mounted on the casing of the discharging device so that the releasing pin is forced against 10 tension of the spring 39 to withdraw the detent 33 from the star wheel 30 and permit its free rotation. This free rotation releases the discharge arm 21 and the catapult cup 20 moves suddenly forward due to the tension built up in the spring 15 23 to hurl the ball deposited in the cup 20 from the projection device.

The lever 28 continues to rotate due to the drive of the motor and the wheel 30 will normally tend to move to a new position after which the 20 spring detent 33 will move into a new aperture 34 to hold the head fixed. Suitable deflecting springs 40 may be used, with which the wheel comes in contact in its continuous rotation, which springs will positively move the head a sufficient 25 amount to such a position that the detent 33 will lock it so that one of the teeth 37 will on the next rotation engage the projection arm 21 to again carry the arm rearward to the dotted line position "A" of Figure 6, where it is again released 30 to project another ball from the device, and so on for each rotation.

The anchor 24 to which the fixed end of the spring is secured is mounted in a suitable adjusting slot in the casing and held by a wing nut 35 42 in any desired position. By relatively adjusting this end of the spring thus moving it in an arc about the shaft 22 the relative tension of the spring 23 may be increased or decreased when wound. The tension of the spring determines 40 the velocity of the ball and in some cases may effect its direction in view of the rapidity with which the trigger or actuating head releases.

It has been found that the catapult arm 21 near the end of its forward stroke is moving very fast 45 and if brought to too quick a stop would become bent and out of position. A speed retarder device is therefore applied to the operating spring housing 37. It preferably consists of an arm 45 of curved shape, having a flange 46 projecting 50 into the path of the catapult arm 21 but near the ball discharge end of its stroke. The arm 45 is more clearly shown in Figure 9 and includes a slotted portion 48 for the operating movement of the spring arm 21, and an aperture 49 in the end 55 which receives one end of the retarder spring 50, the other end of which is fixedly secured in a collar 51 non-rotatably secured to the housing 47, surrounding the spring 23. The spring 50 is so wound that the flange 46 on the arm 45 is in 60 tensioned position when engaged by the catapult arm 21 and yet will move forward slightly during the slowing down of the catapult arm. The housing 47 is held against rotation by the fixed end of the spring 23 which projects through the 65 housing 47 and by the counterspring 52 which is fixed to the anchor 24 held by the frame. This tends to hold the flange 46 sufficiently far forward to prevent premature cutting off of the discharge stroke. The spring 50, tends to quickly 70 reduce the forward movement of the catapult arm and prevents damage to the catapult arm as well as to quickly discharge the ball carried by it.

The balls carried in the neck 14b of the hopper drop down to a cup shaped valve 55 controlled 75 by a gate 56 in the path of the catapult cup 20.

As the gate is moved downward by the rearward movement of the cup, the valve 55 releases the ball 8 which drops freely into the cup.

Soon after the ball is deposited in the cup 20 the pin 36 engages the cam 38 to release the detent 33 and free the star wheel 30, which releases the catapult arm 21 and the energy stored in the spring 23 by the reverse movement, catapults the cup 20 forward to throw the ball from the machine. The time of movement of the ball from 10 the valve to the position at which it is picked up by the cup is equivalent to the movement of the cup to the pick-up position and the sudden change of direction of the ball causes it to stay within the cup until it is finally discharged in the 15 discharge position of the catapult.

The rate that the balls are discharged from the machine depends on the rate of rotation of the shaft 22 which controls the tensioning member 28. The speed of the motor 27 may be varied 20 by any well known means or the gears may be changed for different speed reductions. For effective results, however, a discharge of approximately fifty balls per minute is quite satisfactory and in most cases offers considerable exercise 25 for the player.

As previously stated, the velocity of the balls is varied by the tension of the spring 23 varied by movement of the anchor 24.

The positioning of the balls with respect to the 30 point at which they bounce may be controlled by suitable adjustments 57 and 58 which can control the elevation of the discharge head 14 as well as control the angle in horizontal plane or azimuth angle. It is found that the normal variation in delivery is such to make the game of considerable interest and to require some skill for returning the balls.

It is also possible to mechanically oscillate the head 14 if that is found desirable. One form of 40 apparatus for this purpose includes a belt driven shaft 140 operated by the belt 141 from the driving shaft 59 and to the end of which is a series 35 of gears and eccentric 142. A link 143 is pivoted to the eccentric and in turn is secured to a 45 lever 144 clamped to the head extension 145. As the motor operates the shaft 59, it will be seen that the head will oscillate as desired. Other mechanisms may be substituted for the same purpose.

Although in Figures 4 to 10 the elevating mechanism is not shown, it is to be understood that suitable elevating mechanism may be provided for the continuous filling of the hopper 14a from any suitable sump or receptacle from which the 55 balls are returned. This elevator mechanism is generally shown at 15 in Figure 1.

While no counting mechanism of a separate nature has been shown with this embodiment, it is of course possible to use any of the hereinafter described forms or any other desired form of 60 counting or scoring mechanism. Primarily, however, the layout of Figures 1 to 3 is for tennis, it being understood that the player may observe 65 his returns and score them mentally or merely return the ball for desired training. The discharge device is equally as suitable for other games however, as will hereinafter be described.

In the present invention, the machine has been 70 mounted in the return court and is carried by a desired standard for rigidity. It will be seen, however, that the machine may be made sufficiently light that it can be mounted on a table and it can also be in the center of the table or 75

court. This may also be found desirable by some for training purposes.

A further modified form of court construction is shown in Figures 11 and 12 in which a table 5 60 is used and the projecting machine or gun 14 discharges the balls 8 in such a direction that they will bounce on the table before being returned by the player. The player will drive the balls to the scoring portion of the court by which 10 his skill may be tested.

The scoring in this form of the game is done by suitable plates 62 mounted in the court floor 10 and having different values depending on the relative location and amount of skill required to 15 place the return shots on them. This scoring mechanism, which operates the tell-tale 65 at the top of the court, is more clearly shown in Figures 13, 14, 15 and 16.

In one particular form of construction the 20 plates 62 may be provided with contacts 63 which operate on a second contact mechanism 64 connected in the electric circuit 66. A magnet 67 in the circuit 66 is energized by the closing of the contacts 63 and 64 when a ball strikes the plate 25 62, and this will draw the armature 68 down to release one of a series of number plates or flags 69 which carries an appropriate number. The first flag may have a zero reading, the subsequent flags having readings such as 50, 100, 150, 30 etc.

A separate series of indicators (not shown) may be connected into the other plates 64 and similarly operate flags having multiples of 1000 which being separately indicated on the score board 65 35 will show the total score obtained by repeatedly driving balls onto the plates in the particular locations in the court. In such a construction it is possible to not only practice accurate placement of the return shots but it also makes the 40 game interesting in having a score developed during the play. To increase the difficulty of the play the court may have such blank spots as is found desirable, thus limiting the gross score.

The plates 64 may be replaced by a fine wire mesh slightly raised above suitable contact points 45 or any other electrical device may be used to indicate the contact of the ball returned to the appropriate spot. The tennis ball or even the ping-pong ball may be used in such a game as the return force is quite substantial.

50 This type of scoring depends on contact and is one of the satisfactory ways of determining a score. It may be used with the previous court construction although in amusement parks the tables may be found desirable to give a suitable 55 angle of play and to permit the players to try their skill without moving onto a special court.

In certain games such as table tennis, a longer and narrower table may be found desirable with a modification of the target due to the lightness 60 of the ball. In Figures 17, 18, 19 and 20, we have therefore shown a modified layout of court and target in which the court 10 is provided with a table 70 resembling a table tennis table and having a suitable net 72. The projecting device or gun 73 is located in the rear of the court and may be braced by suitable braces 74 to the end of the table. The target and scoring device 75 is 65 preferably mounted near the end of the table and as shown in Figure 18 at a level with the table.

70 The target may preferably consist of a series of indicators 76 behind which are a plurality of lights 77 which are energized by certain electrical circuits placed in operation by gates 78 behind the ball receiving pockets 79. These pockets line

the scoring device immediately above the table and may have deflecting wire screens 80 which will cause the ball entering one of the pockets 79 to drop onto the gate 78 and complete an electrical circuit with the contacts 82 as shown in 5 Figure 20. The circuit may include the relay 83 which in turn controls the appropriate lights 71 to illuminate the figures 76. The relay may be reset by any desired means.

The pockets are relatively small in size and 10 their different locations will have different values as desired. The arrangement of such an indicator is such that the balls striking near the end of the table and with little bounce enter pockets of the highest value and balls bounced near the 15 net 72 will either not enter a pocket at all or will enter a higher pocket with a lower value. This may be arranged to closely simulate the skill in placement of returns in ping-pong or any other desired game.

20 After the balls pass the switch mechanism, they may pass through the channel 85 to be counted by any desired mechanism and returned to the hopper of the machine. Such counting will also tend to evaluate the skill of the player.

25 A modified form of projecting device is shown in Figures 21 and 22. This form uses a racquet rather than a catapult and may be arranged to give a slight twist or curve to the ball. It is adapted to be mounted in a court as in the previous 30 constructions and will bounce the ball in the playing court. The present construction is more particularly arranged for a game such as tennis.

35 In detail, the ball discharging device includes a hopper 90 to which the balls 8 are automatically fed by the elevator mechanism 91 including the endless chain 92 having the pockets 93 engaging the balls in the return channel 94 and delivering them down the inclined bottom 95 of the hopper to the restricted throat 96 through which the balls must pass one at a time. This hopper is also provided with a cover 97 through which additional balls may be placed or removed. The elevator mechanism may be driven by any desired 40 means such as through the shaft 128 connected to the motor 112.

45 In the bottom of the restricted throat is a slide 98 having a shelf 99 so spaced from the slide that as the slide 98 is moved to uncover the opening 100 to allow a ball to drop out, the shelf 99 contacts with the next ball to prevent it from dropping; thus but one ball is dropped at a time from the hopper and only when the slide 98 is moved in timed relation with the racquet 115. The spring 101 prevents accidental movement of 50 the slide.

55 The projecting device proper includes a stanchion 110 mounted on a suitable base 111 and including a motor 112 which may operate through a clutch mechanism 113 and spring 114 to rotate the racquet 115 after the spring has been appropriately wound and the trigger 118 is released. This gives the bat an impulse type of drive so that it will move only after the spring has accumulated sufficient energy to give a swift blow to the balls which drop into its path.

60 The trigger 118 is released by the lever 119 which is positioned in the path of the collar 113. During the rotation of the motor shaft 117 the 65 racquet is restrained from rotating by the pin 118 which causes the spring 114 to wind, thus drawing the collar upward and at the proper moment, the lever 119 is forced upward to draw the restraining pin 118 out of position. The 70 75

racquet is then free to rotate. This construction is well known in the art and permits any desired tensioning on the spring before the racquet is released.

5 When the racquet commences its rotation it will engage a trigger 120 in the path which operates through a clutch 121 to rotate the shaft 122 on which is mounted an arm 123 operating in turn a link 124 operatively connected to the slide 10 98. As the racquet rotates, therefore, the slide 98 is pulled into the releasing position and a ball will drop through the throat into the path of the bat.

The clutch release lever 126 may be operated 15 by a suitable cord 127 to release the clutch 121 so that the racquet may continuously rotate without moving the slide 98 so that the motor may be left running without discharge of further balls.

While we have described various forms of embodiment of our invention, it will be understood 20 that other forms of embodiment may be used and modifications made in the forms herein described without departing from the spirit of our invention or the scope of our claims which are intended 25 to cover the arrangement of a projecting device adapted to bounce a ball toward the player and a scoring indicating means to indicate the player's score no matter what form these devices are embodied in.

30 The racquet 115 is mounted in the post 130 at the top of the drive shaft 117 by a suitable adjusting nut 131 so that the racquet may be partially rotated for adjustability and for slightly different directional aim of the balls out of the 35 discharge throat 132. This will permit the discharge of the balls to different positions on the court and will add to the complexity of the game. Furthermore, the racquet may be constructed of different well known materials which 40 in striking the ball, will give the twist or curve to the ball which is characteristic of good players.

While we have shown a preferred form of embodiment of our invention, we are aware that 45 other modifications may be made thereto and we therefore desire a broad interpretation of our invention within the scope and spirit of the disclosure herein and of the claims appended hereinafter.

50 We claim:

1. An apparatus for projecting balls in an amusement device which comprises a hopper, means to release one ball at a time from said hopper, and a catapult including a spring arm, 55 means to energize said arm and a ball receiving cup, said ball releasing means being releasable during the catapult spring energizing movement to drop a ball into the cup, and trigger means to release the catapult after a ball has been dropped 60 to the cup whereby balls are thrown from the apparatus in predetermined paths.

2. A ball projecting device for projecting balls in connection with an amusement apparatus 65 which comprises a ball supply chamber, a discharging element, a valve to drop balls one at a time from said chamber to said discharging element, means actuated by contact of the discharging element to operate said valve, means to energize the discharging element, means to 70 release the discharging element when energized, means to regulate the extent of energization of the discharging element and means to again energize the discharging element after discharge, said energizing means being variable to control

the velocity and the rate of discharge of the balls.

3. In an apparatus of the class described the combination of a game court having ball return channels thereon, an indicating means, and a 5 ball projecting device cooperating with said court, said court being divided into a playing zone and a return zone, said ball projecting device including means to project balls into the playing zone of said court and to bounce balls 10 adjacent the player, and said indicating means including means to record the return position of the balls when returned by the player to a point at the return zone of the court and a plurality of electrical devices operated by the returned balls, and means to replenish the ball discharging device from the ball return channels. 15

4. In combination with a game court, a ball projecting device for solo playing of table tennis, tennis and the like, in which the ball is bounced 20 upon the court before return by a player, a scoring mechanism including a plurality of switch members adjacent respective points in the return court and responsive to contact by returned balls, and a plurality of indicators controlled by 25 respective switch mechanisms, said indicators having different values whereby proper returns of balls by the player will energize different value indicators simulating desired playing conditions for the respective games. 30

5. An apparatus for solo playing of games such as table tennis, tennis and the like, which comprises a playing platform for the particular game, a ball projecting device mounted adjacent one end of the platform, simulating one player, 35 a net dividing the platform into a playing zone and a return zone, scoring mechanism within the return zone, said scoring mechanism indicating with variable value the return of the balls into the return zone by the actual player and means 40 to feed the return balls automatically to the projecting device including an elevator mechanism and ball return channels leading to said elevator mechanism.

6. An amusement apparatus which comprises 45 in combination a court simulating a table tennis court, a dividing net, a ball projecting device, a table, means to discharge the ball from said device to bounce said balls on said table at a rate and with a speed to be handled by a player, 50 and a score indicating mechanism in the court opposite the player responsive to contact by balls properly returned to said court by the player to indicate a score for such returns.

7. An amusement device which comprises in 55 combination, a table tennis court and a ball discharging device for discharging balls onto the court for bouncing action, said ball discharging device including means to throw table tennis balls successively in controlled directions directly onto said court, means for driving said throwing means, and means actuated by said driving means to vary the position of said throwing means, whereby successive balls are discharged to different points on the court, and the playing 60 conditions of a table tennis game are simulated. 65

8. An amusement device which comprises in combination, a court simulating a tennis court or the like and a ball discharging device for discharging balls onto the court for bouncing action, said discharging device including means to hold a plurality of balls, means to throw the balls successively directly onto the court in controlled directions, and means operative between the discharge of successive balls to vary the posi- 70 75

tion of said throwing means, whereby successive balls are directed to different points on the court and the playing conditions of a tennis game are simulated.

5 9. An amusement device comprising in combination, a court, a support on one side of said court, a ball discharging device mounted on said support for discharging balls onto the court at various positions in front of a player from which 10 positions the balls bounce to be returned by the player, said device including means to hold a plurality of balls, means to throw the balls successively directly onto the court, means to feed the balls one by one from said holding means 15 to said throwing means, driving means for said feeding and throwing means, and means actuated by said driving means for changing the position of said throwing means whereby successive balls are discharged to different points on the 20 court, and the playing conditions of a tennis game are simulated.

10. An amusement device which comprises in combination, a court, a ball discharging device for discharging balls to a position in the court 25 in front of a player from which the balls bounce to be returned by the player, said discharging device including means to hold a plurality of balls, variable speed means for propelling balls successively directly to predetermined positions on 30 the court, means for transferring a ball from said holding means to said propelling means prior to each actuation of the latter, and means operative between successive discharges to change the position of said propelling means whereby continually to vary the points at which the balls 35 bounce on the court.

11. An amusement device which comprises in combination, a court, a ball discharging device for discharging balls to a position on the court 40 in front of a player from which they bounce to be returned by the player, said discharging device including means to hold a plurality of balls, means to release the balls one at a time, means to engage and propel the released balls directly 45 onto the court, variable energizing means for said engaging and propelling means whereby to discharge the balls at selective velocities, variable speed means to control the speed of operation of the device whereby the frequency of discharge may be varied, and means operative between successive discharges to vary the position of said propelling means whereby successive balls are discharged to different points on the court.

12. An amusement device which comprises in 55 combination, a court, a ball discharging device for discharging balls onto the court from which they bounce to be returned by a player, said discharging device including means to hold a plurality of balls, means to throw the balls successively directly onto the court in controlled directions, means operative between the discharge

of successive balls to vary the position of said throwing means whereby successive balls are directed to different points on the court, and a scoring mechanism for indicating the balls returned by the player to a scoring point. 5

13. In an amusement device for the solo playing of a tennis game or the like, the combination with a game court having an area for the reception of properly played balls of a ball discharging device for discharging balls successively 10 across a portion of the court directly onto another portion thereof so that they are bounced adjacent a player, said discharging device including means for varying the points at which the balls strike the court, and means in the aforesaid area responsive to contact by a ball when returned into said area by the player to indicate a score for such return, whereby the playing conditions of a tennis game are simulated. 15

14. The combination of claim 13 wherein the 20 last recited means comprises a plurality of movable plates located in the court and means responsive to movement of said plates under the impacts of returned balls to indicate the scores for such returns. 25

15. In a game apparatus of the class described, a ball projecting device for discharging balls onto a court which comprises a hopper for a plurality of balls, a restricted conduit below said hopper, valve means to drop the balls periodically and 30 one at a time from said conduit, and means to receive and project the balls successively from said apparatus comprising a spring arm, a ball receiving cup on the outer end thereof, means to move the arm rearward to store energy in 35 said spring, means actuated by contact of the arm during its rearward movement to actuate said valve means, and means operative after a ball has been dropped into said cup to release said arm to project the ball forward. 40

16. An amusement apparatus which comprises in combination, a court simulating a tennis court, a dividing net thereon, a ball projecting device, means to discharge balls from said device and bounce the same on said court at one side of said 45 net at a rate and with a speed to be handled by a player, and a scoring mechanism in the court opposite the player responsive to contact by balls returned into said court to indicate the score of the balls returned by the player to scoring 50 positions, said ball projecting device including an oscillatable arm, a spring connected to said arm, means to tension the spring to control the arm, means to carry a ball on said arm during discharging movement thereof, whereby to direct 55 the ball toward a predetermined portion of the table, and means to feed a ball to said carrying means prior to each discharging movement.
